UNITED STATES PATENT OFFICE.

KARL STAUFENBEIL, OF DUBUQUE, IOWA.

DESIGN FOR A COLLAR-CLIP.

55,214.

Specification for Design. Patented May 18, 1920.

Application filed December 26, 1919. Serial No. 347,610. Term of patent 7 years.

To all whom it may concern:

Be it known that I, KARL STAUFENBEIL, a citizen of the United States, residing at Dubuque, county of Dubuque, State of Iowa, have invented a new, original, and ornamental Design for Collar-Clips, of which the following is a specification, reference being had to the accompanying drawing, forming a part thereof.

The figure is a perspective of a collar clip showing my new design.

I claim:

The ornamental design for a collar clip as shown.

KARL STAUFENBEIL.
